Primary Examiner — Sheryl Lane*Assistant Examiner* — Ieisha N Price(74) *Attorney, Agent, or Firm* — The Dobrusin Law Firm, PC(57) **CLAIM**

The ornamental design for a trowel, as shown and described.

DESCRIPTION

FIG. 1 is a top, right perspective view of the trowel;

FIG. 2 is a top, left perspective view of the trowel;

FIG. 3 is a top view of the trowel;

FIG. 4 is a bottom view of the trowel;

FIG. 5 is a left side view of the trowel;

FIG. 6 is a right side view of the trowel;

FIG. 7 is a front view of the trowel; and,

FIG. 8 is a rear view of the trowel.

The broken lines in the drawings illustrate portions of the trowel and form no part of the claimed design.

The trowel is shown with symbolic breaks in its length. The appearance of any portion of the article between the break lines forms no part of the claimed design.

1 Claim, 4 Drawing Sheets(56)
